CLAIM

The ornamental design for a display screen with graphical user interface, as shown and described.

DESCRIPTION

FIG. 1 is a front view of a display screen with graphical user interface, showing my new design; and, FIG. 2 is a front view of a second image thereof.

The broken lines illustrate structure or features which form no part of the claimed design. The subject matter of this patent includes a process or period in which an image

(Continued)

sequentially transitions into another image. This process or period forms no part of the claimed design.
